[57]**CLAIM**

The ornamental design for an ink ribbon and tape cartridge for a printer, as shown and described.

DESCRIPTION

FIG. 1 is a front, right side and bottom perspective view of the ink ribbon and tape cartridge for a printer in accordance with my new design;

FIG. 2 is a front elevational view thereof;

FIG. 3 is a top plan view thereof;

FIG. 4 is a left side view thereof;

FIG. 5 is a bottom plan view thereof;

FIG. 6 is a right side view thereof;

FIG. 7 is a rear elevational view thereof;

FIG. 8 is a front, right side and bottom perspective view of the tape cartridge portion of the ink ribbon and tape cartridge for a printer of FIG. 1;

FIG. 9 is a front elevational view thereof;

FIG. 10 is a top plan view thereof;

FIG. 11 is a left side view thereof;

FIG. 12 is a bottom plan view thereof;

FIG. 13 is a right side view thereof;

FIG. 14 is a rear elevational view thereof;

FIG. 15 is a front, right side and bottom perspective view of the ink ribbon portion of the ink ribbon and tape cartridge for a printer of FIG. 1;

FIG. 16 is a top plan view thereof;

FIG. 17 is a front elevational view thereof;

FIG. 18 is a left side view thereof;

FIG. 19 is a right side view thereof;

FIG. 20 is a rear elevational view thereof; and,

FIG. 21 is a bottom plan view thereof.
